UNITED STATES PATENT OFFICE

GEORGE H. ISLEY, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS

REGENERATIVE HEATING FURNACE

Application filed February 1, 1930. Serial No. 425,304.

The present invention relates to regenerative heating furnaces, such, for example, as soaking pit and steel heating furnaces, of the general type shown and described in my co-pending application Serial No. 393,683, filed September 19, 1929.

The present invention, as applied by way of example to a gas-fired soaking pit furnace, resides in a novel arrangement of ports and 10 passages, whereby the flame and hot furnace gases are made effective on the articles or materials to be heated in a substantially uniform manner. Other objects and advantages of the invention will be apparent from 15 the following detailed description thereof, taken in connection with the accompanying drawing, in which—

Fig. 1 is a plan view, partly diagrammatic, of a regenerative soaking pit construction in 20 accordance with my invention.

Fig. 2 is a sectional view on the line 2—2 of Fig. 1.

Fig. 3 is a fragmentary sectional view, similar to Fig. 2, of a modified form of my 25 invention.

Fig. 4 is a sectional view on the line 4—4 of Fig. 3.

Like reference characters refer to like parts in the different figures.

In the furnace of the soaking pit type shown by Figs. 1 and 2, the heating chamber which receives the ingots *a*, *a*, or other stock to be heated, is constituted by two substantially parallel portions 1 and 2 which are 30 separated, as shown in Fig. 1, by a partition 3. The upper portion of chamber 1, as shown in Fig. 2, has a port or passage 4, and the chamber 2 has a similarly located port or passage 5, said ports or passages 4 and 5 establishing communication of their 35 respective chamber portions with air regenerator chambers 6 and 7, respectively. The latter are here shown in substantially parallel arrangement, the same as in my afore- 40 said copending application, and in communica- 45 tion at their other ends with suitable drafting and reversing means, here shown as the upwardly-opening ducts 8, 8, each of which is adapted to be supplied with upwardly- 50 directed jets of air, as by means of a suitable

blower 9. Each duct 8 is equipped with a suitable valve or damper 10, Fig. 2, and the positions of these dampers determine the direction of gaseous flow through the furnace. That is to say, when the damper 10 is closed, the air supplied to the duct 8 in question is deflected downwardly, as shown by the full line arrows in Fig. 2, and passes to the furnace by way of said regenerator passage 6. Under these conditions, the other damper 10 associated with regenerator passage 7 is open, so that the air supplied by the blower to the other duct 8 exerts an entraining action on the waste furnace gases to draw them through the regenerator passage 7 for discharge from the upper open end of the duct 8 associated with said passage. To effect reversal of the air supply, it is only necessary to interchange the positions of the two dampers 10, 10, as will be readily understood.

Figs. 1 and 2 show a furnace arranged for the use of producer gas as fuel, and to this end a producer gas supply flue 11 is disposed in transverse relation to the several regenerator passages 6 and 7 of a battery of soaking pits, said supply flue, as best shown in Fig. 2, having a plurality of outlet branches 12, 12, corresponding in number and arrangement to the regenerator passages 6 and 7. Each branch 12 leads from the flue 11 to a port 4 or a port 5, as the case may be, and each branch 12 is controlled, at its junction with the supply flue 11, by a suitable valve 13. It will thus be seen that for operation of the furnace under the conditions illustrated by the full line arrows in Figs. 1 and 2, the producer gas which flows by a branch 12 to the port 4 will form a combustible mixture with the warm air blown in through the regenerator passage 6, and that under these conditions, with the other port 5 of the heating chamber serving as an outlet for waste furnace gases to the regenerator passage 7, the branch 12 leading to said port 5 is shut off from the gas supply flue 11, by closure of the associated valve 13.

Under the conditions above described, the fuel and the air for its combustion enter the

portion 1 of the heating chamber by way of port 4 in the upper part of said chamber, and the resulting flame is obliged to travel downwardly in substantially full length contact with the objects *a*, *a* in said chamber portion 1 in order to reach the chamber portion 2, because, as shown in Figs. 1 and 2, the communication between the two chamber portions is by way of a pair of transverse passages 14, 14 at a much lower level than the ports 4 and 5. Furthermore, the arrangement of the passages 14, 14 is such that the descending gases in chamber portion 1 are made to fan out laterally toward the bottom of said portion 1, because said passages 14, 14, as shown, are in effect lateral extensions of the chamber portions 1 and 2 that pass around both ends of the intermediate partition 3. Therefore in the chamber portion 2, the furnace gases, entering sidewise near the bottom, are obliged, in seeking an outlet from said chamber portion, to rise almost to the top, which insures that the objects *a*, *a* in said chamber portion will be thoroughly and uniformly heated before the gases finally pass out through the port 5 to the regenerator passage 7. This same effective heating of the contents of the heating chamber 1, 2 is obtained when the furnace is reversed, in the manner previously described; under these conditions, the flame and furnace gases entering near the top of chamber portion 2, by way of port 5, are drawn down and spread out as they pass by the passages 14, 14 to the chamber portion 1, and then, entering the latter from the side near the bottom, are drawn upwardly for ultimate discharge through the port 4 into the regenerator passage 6.

In the embodiment of my invention shown by Figs. 3 and 4, the same general mode of operation prevails; in this case however, the communication between the chamber portions 1' and 2' is by way of ports 15, 15 in the lower part of the separating partition 3', so that the flame and furnace gases entering by way of port 4' will have the same generally downward flow in the chamber portion 1', followed by the same generally upward flow in the chamber portion 2', before discharging through the port 5'.

I claim,

1. A regenerative heating furnace comprising a pair of regenerator passages adapted to serve alternatively, as the furnace is reversed, for the inflow of combustion-supporting air, and for the outflow of combustion products, a heating chamber having ports at its upper end communicating with both of said passages, and a substantially vertical partition in said chamber arranged to block off communication between said ports except by way of the extreme lower end of said chamber, whereby in both directions of the flow through said chamber of flame and

hot gases, the latter pass first downwardly, then horizontally, and finally upwardly, to completely envelop the charges in said chamber on both sides of said partition.

2. A regenerative heating furnace comprising a pair of regenerator passages adapted to serve alternately, as the furnace is reversed, for the inflow of combustion-supporting air, and for the outflow of combustion products, a heating chamber having ports at its upper end communicating horizontally with both of said passages, a partition in said chamber between said ports and extending from the top to the bottom of said chamber, and a horizontal passage at the bottom of said chamber connecting the portions thereof on opposite sides of said partition, whereby in both directions of the flow through said chamber of flame and hot gases, the latter enter one of said chamber portions horizontally, pass downwardly therein and then horizontally into the other chamber portion, and finally upwardly in the latter with horizontal discharge therefrom, to envelop completely the charged material in both of said chamber portions.

GEORGE H. ISLEY.
